(57) **CLAIM**

The ornamental design for the hand operated tool handle with an improved tool bit adapter, as shown and described.

DESCRIPTION

FIG. 1 is a perspective view of the hand operated tool handle with an improved tool bit adapter;

FIG. 2 is a front view of the hand operated tool handle with an improved tool bit adapter;

FIG. 3 is a rear view of the hand operated tool handle with an improved tool bit adapter;

FIG. 4 is a left side view of the hand operated tool handle with an improved tool bit adapter;

FIG. 5 is a right side view of the hand operated tool handle with an improved tool bit adapter;

FIG. 6 is a top view of the hand operated tool handle with an improved tool bit adapter; and,

FIG. 7 is a bottom view of the hand operated tool handle with an improved tool bit adapter.

The broken lines in the drawings represent unclaimed environmental subject matter.
